UNITED STATES PATENT OFFICE.

HENRY F. HERMAN, OF CHAPPAQUA, NEW YORK, ASSIGNOR TO IMPERIAL PIANO
PLAYER COMPANY, A CORPORATION OF NEW YORK.

POWER-TRANSMISSION MECHANISM.

1,246,426.

Specification of Letters Patent. Patented Nov. 13, 1917.

Application filed August 20, 1914. Serial No. 857,627.

To all whom it may concern:

Be it known that I, HENRY F. HERMAN, a citizen of the United States, residing in Chappaqua, Westchester county, and State 5 of New York, have invented new and useful Improvements in Power-Transmission Mechanism, of which the following is a specification.

This invention relates to power transmission mechanism and to the coöperative relations and coaction of machine elements, or the moving parts of a mechanical mechanism, in effecting such transmission.

It has for its object the use of electro-magnetism in the connection and actuating of such parts and in the control of their relative coöperation, so that the power may be applied and transmitted or released as desired, and the operation of the machine 10 or mechanism be thus controlled.

The invention may be applied to a wide range of different physical parts, and by means of various mechanical principles, the basic feature of the invention being the 15 provision of a magnetizable element, or unit, such as a magnet or magnet core, as one in a series of coöperating parts, another of said coöperating parts serving as armature to connect or transmit power from 20 its source or a driving element to a driven element or the work to be effected, such magnetizable part constituting a part of either the driving or driven elements and being free to move and coact with the armature constituting a part of the other 25 element and without participation in said movements by the electro-magnetic means employed to energize said magnet.

This is accomplished by transmitting the 30 electric force to said magnet or magnet core across an air gap intervening between said magnet core and electric circuit-windings to energize the same, whereby the magnet core is free to have movement throughout said 35 air gap and within the field of said windings, or circuit coil, independently of movement by said coil and while said coil may remain motionless.

It is obvious that a magnetizable part in 40 such conditions acting as a magnet core may have a great variety of forms and may make various operative connections either physical or by magnetism, with other parts with which it may coact, and that by 45 controlling the electric circuit, through

means to make and break the same the said magnet may be successively energized and deenergized as desired, and thus its coöperative movements be controlled. The parts employed may exist in any relative 50 force and size and the electric current may vary as required.

The movement of the magnet core may be of any nature and of any degree within the electric field of the electro-magnetic 55 windings, such as reciprocating or rotary, or may be transverse to the plane of the windings or parallel therewith, the limitation of movement being the extent of the air gap and the strength of the electro-magnetic means.

It will be seen that the magnetic results are obtained or applied by having the connecting parts of the operative mechanism act as armature to said core as magnet. The 60 said core acts as a connecting medium operatively uniting the said parts and is mechanically connected to one of the same and magnetically to the other as armature, this latter connection being subject to control 65 through the electric circuit.

In this way the operative connection of the parts is releasable by deenergizing the magnet, and the parts may remain in operative contact ready to be again made operative upon again energizing the magnet 70 through the control of the electric circuit.

In the embodiment of the invention illustrated in the drawing accompanying and forming a part of this specification, Figure 90 1 shows in a diagrammatic manner the invention applied to the operative mechanism of a piano-player or player piano; and

Fig. 2 is a detail plan view, partly in section, of an electro-magnet and a portion of 95 the armature shaft.

Similar characters of reference designate like parts throughout the different views of the drawing.

In carrying out the object of the invention as shown in the drawing, an armature shaft 1 of soft iron is continuously revolving in the direction indicated by the arrow 2, under any convenient source of power or driving element of which it may constitute 100 a part. A magnet 3 in contact with the shaft 1 is supported by a stem 4 connected, as at 6, with and depending from a walking beam or lever 5. The lever 5 is pivotally supported, as at 8, in a block 7. Pivotally 105 supported, as at 8, in a block 7.

- connected at the opposite end of the lever, as at 10, is a depending stem 9 having upon its lower end a suitable block 11 adapted to strike and depress a key 50 of a piano.
- 5 A spool or coil support 12 is carried by a fixed supporting member 13, said spool having upon its outer face a channel or recess 25 to receive and hold a wire circuit coil or windings 14 to energize the magnet. Circuit wires 15 and 16 in circuit with a battery 17 lead to said coil spool and are wound thereon as required.

The magnet 3 is in the form of a letter U, or substantially U-shape in cross section, as clearly shown in Fig. 2, and embraces one side or circumference of the spool 12 and coil 14 whereby the circuit coil or windings surround the said magnet as a core. The poles 18 and 19 of the magnet contact with 20 the shaft 1 as armature in a line with the horizontal plane of the axis of the armature; and when energized magnetically adhere or cling thereto.

It will be obvious that the core 3 when energized will cling to the shaft 1 and be driven upward through said magnetic cling in a plane tangent to the armature, as indicated by the alinement of the stem 4, thus imparting linear movement to the core and 25 will thrust or push up the connected lever end and depress the opposite end to which the stem 9 is connected causing the key to be struck by the block 11. Upon deenergizing the magnet it will drop under gravity 30 to its original position and the influence of the piano key as the latter is returned by its spring ready to repeat this operation upon being again energized.

The spool or coil support 12 has upon its 40 central or inner portion an open space 20 which may be of any relative proportions desired, and may be made to accommodate any mechanical parts or machine elements which it is desired to pass therethrough and 45 to allow such movement therein as required by the operative actions of such parts.

As the circuit wires, or magnet windings, are carried upon the external circumference of said spool they will of course surround 50 any part or magnet core placed therein and upon the completion of an electric circuit therethrough will energize the same.

In the embodiment shown in the drawing, the magnet 3 will upon being energized cling 55 to the revolving shaft 1 and will be thereby carried upward within the space 20, in a direction substantially parallel with the planes of the windings of the coil, and substantially at right angles to its longitudinal extent or its length of passage through 60 said windings, the size and shape of said space being designed to accommodate such movement. Also, as shown, the side of the spool embraced by the magnet serves as a

guide to direct and aline the movements of 65 the magnet.

It will be noted that the magnet 3 is energized by the coil 14 across the air gap 20 and that this is done without any coil or winding upon the actual magnet itself, and 70 without the use or intervention of any circuit wires or windings other than those upon the spool 12 separated from the magnet by an air gap.

The spool 12 is mounted or supported in 75 fixed position, as upon the support 13, and does not move or participate in the movements of the magnet. The advantages of these arrangements are many. All physical connections or circuits, such as flexible wires, 80 movable joint connections, and friction surface contacts, are avoided in energizing the magnet, thus disposing of many circuit troubles and also freeing the moving parts from hampering restrictions upon their 85 action as well as opening a field to the successful use of magnets in co-operative mechanism of many kinds where not now employed.

The magnet is energized by circuit conductor wires 15 and 16 in circuit with the battery 17 and this circuit, in the present instance, is controlled by means of the usual perforated paper music control sheet, indicated at 28. This control sheet is wound 90 from a spool 26 onto a take-up roll 27 and passes over a tracker-bar 23. This tracker-bar is of non-conductor material pierced by pins of conductor material, one for each piano key, one end of the pins being flush 95 with the upper face of the tracker-bar and at their opposite ends projecting, as at 25, at which point they are connected with the circuit wires 16, one circuit for each key. The circuit wire 29 connects with a brush 100 21 bearing a line of conductor wires 22 upon its face, all of which wires are constantly in circuit and contacting through the perforations in the paper control sheet with the pins 24 in the tracker-bar as said control 105 sheet in its progress successively exposes said pins to such brush.

It will be seen that upon making such contact the circuit is completed in case of each key, or more, so contacting, and thereupon the magnet is energized and clings to the revolving shaft, thus striking the key. Upon the passing of the perforation the circuit is broken and the magnet deenergized and returns to initial position.

Having thus described my invention, I claim:

1. In a power transmission mechanism, the combination with a driving element and a driven element, of a reciprocable magnetizable core connected to one of said elements; a stationary electric circuit coil surrounding said core with a space within the

coil to permit the core to have movement therein substantially parallel with the planes of the windings of said coil; and a revolute armature connected to the other element with which the core coacts when energized to magnetically connect the driving and driven elements.

2. In a power transmission mechanism, the combination with a driving element and 10 a driven element, of a revolute armature included in one of said elements; a magnetizable core connected to the other element and when energized coacting with the armature to magnetically connect the driving and 15 driven elements; and a fixed electric circuit coil for said core relative to which coil the core has reciprocable movement in a direction substantially parallel with the planes of and within the windings of the coil.
- 20 3. In a power transmission mechanism, driving and driven elements; a magnetizable core mechanically connected to one of said elements and when energized magnetically connected to the other element; and an 25 electric circuit coil to energize the core, said core constructed to have a space between the coil and core to permit the core to have independent movement within the coil in a direction substantially parallel with the wind- 30 ings of the coil.

4. In a power transmission mechanism, the combination with driving and driven elements, of a continuously revolute shaft 35 of magnetizable material constituting a part of one of said elements; a reciprocable magnetizable core connected to the other element to contact with the shaft in a line with the horizontal plane of the axis of the shaft and magnetically coact with the shaft to 40 have reciprocatory movement in a plane tangential to the periphery of the shaft; and an electric coil relative to which the core has movement in a direction substantially parallel with the planes of the windings of the 45 coil.

5. In a power transmission mechanism, the combination of driving and driven elements; a continuously revolute armature constituting a part of one of said elements; 50 a reciprocable magnetizable core constituting a part of the other element and when energized coacting with the armature to operatively connect the driving and driven elements; and an electric circuit coil for the 55 core within which coil the core moves without participating movement by the coil in a direction substantially parallel with the windings of the coil.

6. In power transmission mechanism, a 60 continuously revolute armature operatively connected with coacting parts of a motive mechanism, a reciprocable magnetizable core also operatively connected with coacting parts of a motive mechanism and mag-

netically coacting with the armature to connect the coacting parts of the core with the coacting parts of the armature, an electric circuit coil surrounding said core and energizing the same, said coil being supported in a fixed position independent of the core 70 and having an interior open space in which space said core when energized is moved by the armature through the magnetic cling of the core with the armature in a direction substantially parallel with the windings of 75 the coil and transverse to the axis of the armature.

7. In a power transmission mechanism, the combination of a continuously revolute armature shaft operating as a driving element; a reciprocable magnetizable core connected to and operating with a driven element and when energized coacting with the armature shaft to connect and impart movement from the driving to the driven element; and a fixed electric circuit coil surrounding the core to energize the latter, said coil having a space interior thereof in which the core reciprocates in a direction substantially parallel with the planes of the windings of the coil without coöperating movement by the coil.

8. In a power transmission mechanism, the combination with driving and driven elements, of a continuously revolute armature shaft operating with the driving element; a reciprocable magnetizable core connected to and operating with the driven element and when energized magnetically coacting with the armature shaft to transmit the rotary movement of the armature to linear movement of the core; a fixed spool surrounding said core with a space interior thereof; and electric circuit windings around said spool to energize the core, whereby said core may reciprocate within the spool and coil in a direction substantially parallel with the windings of the coil without participating movement of the coil.

9. In a power transmission mechanism, the combination with driving and driven elements, of a continuously revolute armature shaft operating with the driving element; a reciprocable magnetizable core operating with the driven element and when energized magnetically coacting with the armature shaft to impart movement from the driving through the shaft to the driven element through the core; a spool surrounding said core with a space interior thereof; a support for the spool to maintain it in a fixed position; and an electric current conductor wound around said spool to energize the core whereby the core may reciprocate within and independent of the spool and conductor windings in a direction substantially parallel with the conductor windings.

10. In electromagnets, a magnetizable core,

- 4
- a continuously revoluble armature coacting therewith, an electric circuit coil surrounding said core having an opening interior of said coil whereby said core may make reciprocating movement within the coil in a direction substantially parallel with the planes of the winding of the coil. 5
11. In electro-magnets, a magnetizable core, an electric-circuit coil surrounding said core and energizing the same, a fixed support for the coil, said coil having an opening within its inner portion to permit the core to have movement therein in a direction substantially parallel with the planes of the 10 windings of and without moving said coil; and an independent source of power to impart movement to said core. 15
12. In a power transmission mechanism, the combination of a continuously revoluble 20 armature, an electro-magnet including a core supported to have reciprocatory movement with the pole faces thereof to contact with the armature in a line parallel with the axis of the armature to transmit rotary movement of the armature to movement of the magnet core through the magnetic cling of the core to the armature, and means to 25 energize said coil. 30
13. The combination of a continuously revoluble armature and an electromagnet including a U-shaped core supported with the pole faces to have contact with the periphery of the armature in a line parallel with the axis thereof and magnetically cling thereto when energized to transmit movement from one to the other. 35
14. The combination of a continuously revoluble armature and an electromagnet including an energizing coil and a core of U-shape in cross section supported with the pole faces to have contact with the armature in a line parallel with the axis thereof and magnetically cling thereto when energized to transmit movement from the armature to the core. 40
15. The combination of a continuously revoluble armature and an electromagnet including an energizing coil and a core of U-shape in cross section supported independently of the coil and armature with the pole faces to have contact with the armature in a line parallel with the axis of the armature and magnetically cling thereto when energized to transmit movement from one to the other. 45
16. The combination of a continuously revoluble armature and an electromagnet including a core of U-shape in cross section supported independently of the armature with the pole faces to have contact with the armature in a line parallel with the axis of the armature and an energizing coil for the core having no connection with the core, said magnet core when energized magnetically clinging to the armature to have movement imparted thereto from the armature without participating movement of the energizing coil. 50
17. The combination with a source of electricity, of a continuously revoluble armature; an electromagnet in circuit with the source of electricity supported independent of the armature with the pole faces to have contact with the armature in a line parallel with the axis thereof and a make and break contact in the circuit. 55
18. The combination with a source of electricity, of a continuously revoluble armature; an electromagnet in circuit with the source of electricity supported independent of the armature with the pole faces to have contact with the periphery of the armature in a line parallel with the axis thereof; a make and break contact in the circuit; and means to control the making and breaking of the circuit said contact to open and close the circuit. 60
